UNITED STATES PATENT OFFICE.

WILLIAM H. STAATS, OF COLONIE, NEW YORK.

RECOIL-CHECK FOR VEHICLES.

No. 872,544.

Specification of Letters Patent.

Patented Dec. 3, 1907.

Application filed February 19, 1907, Serial No. 358,250.

To all whom it may concern:

Be it known that I, WILLIAM H. STAATS, a citizen of the United States, residing at Colonie, Albany county, State of New York, have invented certain new and useful Improvements in Recoil-Checks for Vehicles, of which the following is a specification.

My invention relates to recoil checks and consists of a recoil check in which the power 10 to resist the upward movement of the carriage body is due to a vacuum and in means for securing this result as fully set forth hereinafter, and as illustrated in the accompanying drawing in which:

Figure 1 is a sectional elevation of my improved recoil check; Fig. 2 is an outside view showing the same applied to a vehicle.

The device consists of a cylinder A, the ends preferably closed by screw caps a, c and 20 a piston D connected to a piston rod E, the cylinder being so closed against the inlet of air that the piston can only be raised by creating a vacuum beneath it. The return of the piston to its lowest position is facilitated 25 by a spring f coiled around the piston rod and bearing against the piston and the head a of the cylinder, and in order to insure the exhaust from beneath the piston of any air which may find its way below the piston, 30 thus equalizing the pressure on both sides of the piston as the latter returns to its normal position, the piston is provided with a port and a valve h opening upward, the valve stem being suitably guided in a bracket j and 35 depressed by a spring d.

The parts are so constructed that the lower end of the cylinder may be connected to the axle of the vehicle and the upper end to the body or an attachment thereof. As shown, 40 there is a lug k on the bottom cap of the cylinder, which lug has a transverse opening x for the passage of a bolt m, which extends through the ears of a clip n and the clip may be tightened upon the axle of the vehicle by 45 means of a nut p turning on threads of the bolt which, therefore, serves both to tighten the clip and connect the cylinder to the axle.

One means of connecting the piston with the carriage consists in providing the piston 50 rod above the cylinder with a cap q, with which is formed a loop b adapted to be connected by a strap s or otherwise to a loop on or to any part of the body of the vehicle.

When the device is arranged upon the vehicle the flexible strap connection s permits a

certain amount of movement downward of the vehicle without affecting the device, but when, owing to any jolt the body of the vehicle tends to rise suddenly the strap will be tightened and the piston will be carried upward in the cylinder until the pressure upon the piston resulting from the vacuum below overcomes the force of the momentum and arrests the body, but with a slow and almost imperceptible resistance, thereby avoiding 60 the jolts and jerks, the discomfort and the strain of the parts which result when no recoil check is employed. It will be seen that in this case the resistance to the movement is not due to compression of the air or to the 70 use of valves (the valve h serving merely to prevent an accumulation of air below the piston), and therefore after the device is once arranged and put in operation there is nothing in it which will get out of order and render it inoperative.

To avoid the shocks or noise which would result from the sudden bringing of the cap q against the head of the cylinder I interpose a washer or cushion g which may be a disk of 80 rubber, felt, or other suitable material. This also serves as a packing around the piston to prevent the inlet of dust to the cylinder.

The spring coiled about the piston rod tends to insure the depression of the piston 85 with a quick movement as soon as the stress upon the strap is relaxed, but this need not always be employed as the air pressure due to the vacuum below the piston will tend to carry the latter downward. If any air 90 should find its way below the piston, however, the air can escape through the check valve h and the spring insures the full descent of the piston.

Without limiting myself to the precise construction and arrangement of parts shown, I claim:

1. The combination in a recoil check, of a closed cylinder, a piston, a piston rod extending through the head of the cylinder and 100 provided with a cap, a spring between the piston and the cylinder head, means for connecting the cylinder and the cap to a vehicle, and a washer interposed between said cap and cylinder head.

2. The combination in a recoil check, of a cylinder closed at the ends, a piston and piston rod, the piston having a port and check valve opening upward, a spring coiled around 105 the piston rod and bearing upon the piston,

105

110

and means for connecting the piston rod with the body of the vehicle and the cylinder with the axle.

3. The combination in a recoil check, of a closed cylinder, piston, piston rod, a perforated lug at the bottom of the cylinder, a clip adapted to encircle the axle and a bolt passing through the ends of the clip and through the said lug, a cap at the upper end

of the piston rod provided with a loop, and a washer at the top of the cylinder, for the purpose set forth.

In testimony whereof I affix my signature in presence of two witnesses.

WILLIAM H. STAATS.
